US0D1064997S

(12) **United States Design Patent** (10) Patent No.: **US D1,064,997 S**
(45) Date of Patent: ** Mar. 4, 2025

(54) **VEHICLE WHEEL**

(71) Applicant: **Ford Global Technologies, LLC**,
Dearborn, MI (US)

(72) Inventors: **Mark Kaski**, Royal Oak, MI (US);
Robert Lesser, Wixom, MI (US); **Dean**
Carbis, Bloomfield Hills, MI (US)

(73) Assignee: **Ford Global Technologies, LLC**,
Dearborn, MI (US)

(**) Term: **15 Years**

(21) Appl. No.: **29/851,081**

(22) Filed: **Aug. 25, 2022**

(51) LOC (15) Cl. **12-16**

(52) U.S. Cl.

USPC **D12/211**

(57) **CLAIM**

The ornamental design for a vehicle wheel as shown and described.

DESCRIPTION

FIG. 1 is a front elevational view of a vehicle wheel showing our new design; and,

FIG. 2 is a perspective view thereof.

The claimed design is indicated by the relatively dark portions in the figures. The de-emphasized and relatively light portions form no part of the claimed design.

1 Claim, 2 Drawing Sheets
